DESIGN FOR A CHINA OR EARTHENWARE DISH.

Design No. 13,716, dated March 13, 1883.

UNITED STATES PATENT OFFICE.

JOSEPH CHETWYND, OF EAST LIVERPOOL, OHIO.

DESIGN FOR A CHINA OR EARTHENWARE DISH.

SPECIFICATION forming part of Design No. 13,716, dated March 13, 1883.

Application filed December 26, 1882. Term of patent 7 years.

To all whom it may concern:

Be it known that I, JOSEPH CHETWYND, a citizen of the United States, residing at East Liverpool, in the county of Columbiana and State of Ohio, have invented and produced a new and original Design for China and Earthenware Dishes, of which the following is a specification, reference being had to the accompanying photographs, forming part thereof.

Figure 1 is a side view of a cover-dish made after my said designs. Fig. 2 is a top view of the cover of the same; and Fig. 3 is a side view of the said dish without the cover to the same, these three views being deemed necessary to fully illustrate my design.

The purpose of the application in this case is to secure a patent for the design herein described to cover all the pieces in dinner, tea, and toilet sets, to which the said design is adapted,

also cuspids, to wit: cover-dishes, souptureens, sauce-tureens, gravy-boats, pickle-dishes, casseroles or round cover-dishes, jugs or pitchers, butter-dishes, tea-pots, sugar-bowls, cream-pitchers, and all articles making up toilet-set. 25

I claim—

Design for dishes composing dinner, tea, and toilet sets, and cuspids, as enumerated hereinbefore, the same consisting of scalloped, oval, or circular line, with surface fluted to correspond with scalloped lines, also the double line at edge of cover and shoulder of dish with indentations at each flute. 30

JOSEPH CHETWYND.
